[57] CLAIM

The ornamental design for a exercise cable set, as shown and
described.

DESCRIPTION

FIG. 1 is a perspective view of an exercise cable set, showing my new design, wherein the broken line showing of
the additional exercise equipment is for illustrative purposes
only and forms no part of the claimed design.FIG. 2 is a right side elevation view thereof, the left side
elevation view being a mirror image thereof;

FIG. 3 is a bottom plan view thereof;

FIG. 4 is a front elevational view thereof; and,

FIG. 5 is a rear elevational view thereof.
